UNITED STATES PATENT OFFICE.

BRONISLAW GWOZDZ, OF SCHÖNEICHE, NEAR BERLIN, GERMANY.

THERMO-TELEPHONE OR THE LIKE.

1,152,627.

Specification of Letters Patent.

Patented Sept. 7, 1915.

Original application filed August 15, 1911, Serial No. 644,243. Divided and this application filed November 15, 1912. Serial No. 731,556.

To all whom it may concern:

Be it known that I, BRONISLAW Gwozdz, a subject of the Czar of Russia, residing at Schöneiche, near Berlin, Germany, have invented certain new and useful Improvements in Thermo-Telephones or the like, of which the following is a specification.

My invention relates to thermo-telephones or the like of the type described in my 10 United States Patent No. 998965, and is a division of my application No. 644,243, Aug. 15, 1911.

In the examples as described and illustrated in this patent a block-like body is used, which consists of only one part and is produced for instance by a casting process as soon as the shape of the Wollaston wire has been determined and the wire is placed in a mold. In such constructions the Wollaston wire cannot be removed afterward from the cast. In many instances however it may be preferable to prepare the block-like body, for instance by making it of individual parts, which, when united, secure the 20 Wollaston wire in place.

Some embodiments of the invention are represented by way of examples in the accompanying drawings, in which—

Figures 1, 2 and 4 show forms in which the body surrounding the Wollaston wire consists of two or more previously prepared parts. Fig. 3 shows another form of a previously prepared block. Figs. 5 and 6 show various forms of the Wollaston wire adapted to be used in the prepared forms of body as illustrated in Fig. 4 and Figs. 7, 8 and 9 show bodies of a flat form, several of which when placed one beside another result in numerous wire bows of great 40 capability of performance.

In Figs. 1 and 2 the block-like body consists of two halves 29, 30 of a cylinder, between which the suitably-shaped Wollaston wire 31 is arranged in the manner shown 45 in the figures. When these two semi-cylindrical bodies are placed one against the other with a certain force, the wire or the limbs thereof are pressed to a certain extent into the material of the cylindrical body 50 and are held securely, especially as the limbs of the Wollaston wires may be bent in any form as represented in my co-pending application, so that the wire is prevented from being withdrawn. For uniting and securing 55 these two halves of the block I provide

the holder 32 of any resisting material, preferably of metal, shown in Fig. 2. The two halves of the block are inserted in the holder by employing pressure, to which end the holder and the block or only one of the 60 two may be formed slightly conical along its entire length or only at one end. If preferred the holder and also the halves of the block may be provided with a screw-thread so that the two halves of the block can be 65 screwed into the holder. It is to be understood that the position of the halves of the block relatively to the Wollaston wire 31 is regulated by employing templets or molds, so that a wire bow 33 is produced of a quite 70 definite length which subsequently projects alone out of the block-like body and is alone subjected to the corrosive process.

Fig. 3 shows another form. Here I employ a previously prepared block 11 having two holes 34 through the same for receiving the limbs 31 of the Wollaston wire. These holes may be of such a size that the wire can be readily passed through them. The block 11 preferably consists of a somewhat yielding material, such as cork, india-rubber and the like, so that when this block is placed in a holder, as represented in Fig. 2, the block is subjected to a certain compression. In consequence of this compression the body is not only securely held in its holder, but the limbs of the Wollaston wire are firmly clamped so that they cannot possibly be shifted. The length of the wire 80 bow 33 projecting from the block is determined here also by means of a templet or mold, so that here also uniform products 85 can be turned out on a large scale. If the block-like body does not consist of acid-proof material, before it is inserted in a holder and, possibly, before the insertion of the Wollaston wire it may be provided with an acid-proof coating as was described above. Likewise, the holder of the block 90 may be similarly coated. Of course in the form shown in Fig. 3 the block may be either pushed axially into its holder or screwed therein; in the latter case, however, only the holder must have a screw-thread because in 95 consequence of employing yielding material the body will at once enter into the screw-threads.

Figs. 4, 5 and 6 show another embodiment in which the Wollaston wire is secured, and the length of the wire bow subsequently 100

110

to serve as the hot wire is determined in a specially simple and uniform manner. As Fig. 4 specially shows, the one half 29 of the block-like body is provided with projections 35, while the other half 30 has corresponding recesses, so that when the two halves are placed together the projections 35 enter into the recesses 36. These projections 35 which may be of any desired shape, and of which there may be any desired number, simultaneously serve for securely positioning the Wollaston wire itself. By means of pressure, bending, punching and like operations the Wollaston wire may have imparted to it a form adapted to the projections 35, *e. g.* that shown in Figs. 4 and 5, having bends 37 of such size and so arranged that they can embrace the corresponding projection 35. Simultaneously, owing to the Wollaston wire being held in this manner by the projections the length of the wire bow projecting from the block after the two halves of the block have been united will obviously be determined. As mentioned above, the projections 35 may have any desired shape. A preferable form is one in which the Wollaston wire shown in Fig. 6 can be employed, said wire having lug-like projections 38 which are to be inserted into corresponding recesses in the projections 35. The wire is thereby secured in an exact and immovable position. The two halves of the block are united and secured by a holder as described above with reference to Fig. 2. It is of course clear that when a relatively very thick Wollaston wire is employed the abutting faces of the two halves of the block may be provided with groove-like recesses which correspond to the shape of the Wollaston wire, so that when the two halves of the block are placed together a groove is formed which exactly corresponds to the shape of the Wollaston wire.

The mode of assembling individual parts securing between them, when united, the Wollaston wire may also be used according to my invention when it is desired to form a hot-wire device of great capacity comprising a plurality of parts and a plurality of efficient hot-wires. Such forms of my invention are shown in Figs. 7-9. The cast which carries the Wollaston wire, the number of whose bows and, consequently, the shape of the same, may be as desired, preferably has the form of a flat rectangular disk, so that a plurality of such disks can readily be placed one beside another. In the illustrative embodiment shown in Fig. 7 the disk is formed by two halves 29 and 30, between which the wire is placed in the manner shown in Fig. 4. As shown in the upper part of Fig. 7, the halves of the block preferably have in their abutting faces grooves 30' whose depth is equal to half the diameter of the Wollaston wire and whose shape

corresponds to the section thereof. The halves of the block to be united are here also preferably provided with projections 35 and recesses 36 which assure their correct relative position when they are united. In the 70 illustrative embodiments shown in Figs. 8 and 9 a yielding material, such as cork, india-rubber or the like, may be used, as in the embodiment shown in Fig. 3. The wire has two bows 41 which project out of the cast 39 and are connected one with the other by a loop 42. The latter and the limbs 40 of the wire are in the cast. Such disk-like hot wire devices made according to either Fig. 7 or Fig. 8 are then inserted in the manner which will be understood from Fig. 9 and from the description with reference to Fig. 2, in a metal holder 32, any suitable number of the devices being placed one beside another and the projecting bows 41 resting in a 85 mold provided with suitable recesses. The holder 32 may be cylindrical or angular and is preferably simultaneously used as a contact-piece, one of the Wollaston wires, *e. g.* 40', being metallically connected with the 90 holder. The remaining wire ends are united in the manner understood from Fig. 9 by twisting or soldering them together, or otherwise, and thereby connected in the requisite manner, and lastly, a loop 40'' is 95 made, preferably likewise out of the Wollaston wire, which projects somewhat toward the edge of the holder 32. The entire device is now filled with a suitable mass which, on the one hand, unites the various 100 hot-wire devices, and, on the other hand, produces out of these individual devices together with the holder 32 one compact entirety, from which a large number of hot wires projects on the one side, while on the 105 other side only the loop 40'' projects which is for use as a contact-piece.

In hot-wire device as shown, in which the hot wire proper has the form of one or more wire bows projecting from one part of the block-like cast, it is possible that this fine hot wire, which is scarcely visible, may be injured. In order to prevent this and to render such hot-wire devices capable of being readily packed and despatched and, also, to be able readily to insert and remove them from a telephone I prefer to employ a special protecting device or guard. This is a simple cap rendered elastic by means of incisions or in other manner, so that it can be pushed tightly on the block-like cast and subsequently removed therefrom. This cap preferably has a projecting edge so that it can be readily grasped by the fingers or the finger-nails. The bottom of the cap is 115 formed as a bell whose shape approximately corresponds to the wire bow, so that the latter securely rests in the bell and nowhere contacts with the wall of the cap. This cap 120 may be made of any desired material, *e. g.* 125 130

aluminium, celluloid or the like, and is preferably placed on the block immediately after the hot-wire device has been made, so that the hot wire is placed in safety and 5 the hot-wire device can readily be packed and despatched. As soon as the hot-wire device is placed in a telephone the protective cap is, of course, removed.

In the above, it has been stated that the 10 variously constructed hot-wire devices are intended for thermo-telephones. It is, however, obvious that such hot-wire devices or those having differently shaped cast bodies can also be employed for all other apparatus 15 in which electrothermic actions occur, *e. g.* for bolometers and the like. The employment of these hot-wire devices in the manner last described is therefore also comprehended in the present invention. Further, a 20 Wollaston band instead of a Wollaston wire may obviously be employed within the scope of the invention.

What I claim is:—

1. In a thermo-telephone or the like the 25 combination with a body consisting of two halves, of a Wollaston wire separately mounted between the halves, said halves having means for assuring the correct relative position thereof, when united, and 30 means for securing the wire in the said body.

2. In a thermo-telephone or the like the combination with a body consisting of two parts, of a Wollaston wire separately mounted between the parts, the parts being provided with projections and recesses for assuring their correct relative position when 35 united, and means for securing the wire in the said body.

3. In a thermo-telephone or the like the 40 combination with a body consisting of two parts, of a Wollaston wire separately mounted between the parts, the parts being provided with projections and recesses for assuring the correct relative position of the 45 parts and of the wire, and means for securing the wire in the said body.

4. In a thermo-telephone or the like the combination with a body consisting of two

halves, of a Wollaston wire separately mounted between the halves, the halves being provided with projections and recesses for assuring the correct relative position of the halves and of the wire, and a holder surrounding the body and securing the said wire in the body. 50

5. In a thermo-telephone or the like the combination with a body consisting of two parts, of a Wollaston wire separately mounted between the parts, the parts being provided with projections and recesses for assuring the correct relative position of the parts and of the wire, and a cylindrical holder surrounding the body and securing the said wire in the body. 55

6. In a thermo-telephone or the like the combination with a body formed of a plurality of bodies each consisting of two halves, of Wollaston wires separately mounted between the halves, the latter being provided with projections and recesses 60 for assuring the correct relative position of the halves and of the wires, the wires of the bodies being electrically connected in a suitable manner, and a holder securing the wires in the bodies. 70

7. In a thermo-telephone or the like the combination with a body formed of a plurality of bodies each consisting of two halves, of Wollaston wires separately mounted between the halves, the latter being provided with projections and recesses for assuring the correct relative position of the halves and of the wires, the wires of the bodies being electrically connected in a suitable manner, a holder securing the wires in 80 the bodies, one end of the connected wires being attached to the holder and the other end projecting out of the holder. 85

In testimony, that I claim the foregoing as my invention, I have signed my name in 90 presence of two subscribing witnesses.

BRONISLAW GWOZDZ.
